UNITED STATES PATENT OFFICE.

LESTER H. MILES AND JAMES W. BAYLESS, OF LOS ANGELES, CALIFORNIA.

SIREN AND ATTACHING MEANS THEREFOR.

Application filed March 16, 1925. Serial No. 15,798.

To all whom it may concern:

Be it known that we, LESTER H. MILES and JAMES W. BAYLESS, citizens of the United States, residing at Los Angeles, in the county of Los Angeles and State of California, have invented a certain new and useful Improvement in Sirens and Attaching Means Therefor, of which the following is a full, clear, and exact description, reference being had to the accompanying drawings.

This invention relates to sirens and attaching means therefor.

The general object of the invention is to provide an improved siren and operating means wherein the parts are simply constructed and are highly efficient.

A further object of the invention is to provide a fixed stator having a rotor movable therein, wherein the parts are of improved construction.

Another object of the invention is to provide a siren together with attaching means wherein the attaching means includes a shaft offset with respect to the axis of the rotor.

Another object of the invention is to provide a siren including a rotor and a stator together with a driving pulley, all arranged in a novel manner.

Another object of the invention is to provide an improved attaching means for a siren together with a novel operating means therefor.

Another object of the invention is to provide an improved bearing support for the rotor of a siren.

Other objects of the invention will be apparent from the following description taken in connection with the accompanying drawings wherein Fig. 1 is a central sectional view through a siren embodying the features of our invention; Fig. 2 is an elevation showing a siren with the cover plate removed; Fig. 3 is a fragmentary top plan view showing the offset supporting member; Figs. 4 and 5 are fragmentary details showing the openings communicating with the cavities in the rotor; Fig. 6 is a plan view of the siren and operating parts therefor; Fig. 7 is a side elevation showing the siren and the operating members; Fig. 8 is an enlarged detail showing the portion of the operating member and Fig. 9 is a sectional view showing a detail of the fastening member.

Referring to the drawing by reference characters, we have shown a siren embodying the features of our invention at 10. This

siren comprises a stator which includes a base member 11 having a peripheral flange thereon. A cover plate 14 is removably held upon the flange 12 by means of screws 15. The cover is shown as provided with a horn 16 thereon and across the mouth of this horn we secure a wire gauze disc 17.

The base member includes a boss 18 which is integral therewith and adjacent the boss 18 but offset with respect thereto, is a holding lug or boss 19. The boss 18 is drilled out to provide an aperture 21 which receives a drive shaft 22. This drive shaft is provided with a shoulder 23 upon which one member 70 of a ball race 24 is fitted while the other member of the ball race 24 is fitted in a rabbet 25 in the boss 18. In a similar manner a ball race 26 is arranged in a rabbet 27 and a dust cap 28 is secured over the ball race 26. 75

The rotor which is an important feature of our invention, is shown at 30. This rotor comprises a disc 31 having a peripheral flange 32 thereon and having a hub 33 arranged to fit over the shaft 22. The hub 33 80 is recessed to save weight and the end thereof engages the member of the ball race 24, which is in engagement with the shoulder 23. A nut 35 serves to hold the parts in the position described. The other end of the 85 shaft 22 is threaded as at 36 and a nut 37 holds the inner member of the ball race 26 in position against the shoulder in the rabbet 27.

The threads 26 are continued to the end of 90 the shaft and upon these threads we arrange locking nuts 40 which engage a bearing plate 41 which serves to hold flexible discs 42 adjacent another bearing plate 43 which plate is held against movement by locking nuts 44. 95 The arrangement is such that the bearing assembly is locked upon the shaft 22 thus preventing vibration and at the same time, the flexible discs 42 will engage a driving member and are mounted for adjustment longitudinally along the shaft. 100

The rotor 30 as previously stated is provided with a peripheral flange 32 which is connected by means of ribs 45 with the hub 23. The ribs 45 in conjunction with the disc 31 provide a plurality of pockets for receiving air and adjacent the outer end of each pocket a part of the flange 32 is removed to provide passageways 50 for air. The surface of the flange defines the passageways 50 110 which are preferably tapered as at 51. The outer flange 12 of the base member 11 is also

provided with slots 54 which correspond in peripheral spacing with the slots 50 previously described. The portions of the flanges 54 are beveled as at 55 in a manner similar to the bevel 51 but in a direction reverse thereto.

The ribs 45, as will be noted by referring to Fig. 1, are cut away at 60 to produce a pocket 61 in front of the horn 16. This produces a superior siren and this pocket feature we deem of considerable importance.

The boss 19 is provided with an aperture 62 through which a supporting shaft 63 or clamping member extends. This clamping member is provided with a base 64 which may have threaded bosses 65 thereon for securing it in place.

The shaft 63 is provided with upper and lower sliding supporting means shown as 20 collars 66 and 67 which are held in position by set screws 60. The lower supporting collar has a portion thereon engaging the body to maintain the body in proper position. A spring 70 is interposed between the 25 collar 67 and the upper portion of the boss 19 and the ends of this spring are bent as at 71 to fit within recesses in the boss 19 and the collar 67 respectively.

From the foregoing description it will be 30 apparent that when the base 64 has been secured in position that the set screws 68 may be released and the boss 19 adjusted to proper position on the shaft 63. After this adjustment has been shifted, the supporting means 66 and 67 will be secured in place by the set screws 68 to hold the siren in operative position.

The under surface of the boss 19 is provided with a set screw 75 which is adapted 40 to engage the lower set screw 68 to limit the swinging movement of the base member with respect to the holding lug 19. The spring 70 is so arranged on the shaft that its engagement with the collar 67 and the 45 boss 19 tends to turn the siren with the lower set screw 68 in engagement with the set screw 75 as shown in Fig. 3.

In order to drive the siren it is preferably mounted with the flexible discs against the 50 fly wheel 80 of a gasoline engine.

The base member 11 is shown as provided with a bracket 81 which has a universal connection 82 thereon. This connection 82 has a link 83 secured thereto which passes 55 through a pin 84, mounted for movement on a bell crank 85 shown in Figs. 8 and 9. The bell crank is adapted to be supported on a shaft 86 and may be rocked by means of a rod 87 which has a push button 88 thereon. The rod 87 preferably passes through 60 the bottom of the body of the vehicle 89. The link 83 extends beyond the pin 84 for some distance and has a spring 90 surrounding it. This spring is retained by a 65 washer 91 which engages a cotter pin 92.

A cotter pin 93 on the link 83 engages the pin 84.

A spring 94 is preferably connected through a bar 95 with the bracket 81 so that it will aid in returning the disc 42 to inoperative position.

In Fig. 6 the device is shown in operative position. When the operator wishes to sound the siren he will push upon the button 88 thus rocking the bell crank 95 and causing a compression of the spring 90. This will exert a pull upon the universal joint 82 and will turn the siren about the shaft 63 bringing the disc 42 in engagement with the fly wheel 80 to rotate the rotor.

The arrangement including the spring 90 is of extreme importance as regardless of the quickness or amount of force exerted on the button 88 only a predetermined pull can be exerted on the rod 83 thus preventing 85 breakage of parts.

Referring again to Fig. 1 it will be noted that the flange 32 of the rotor is in close proximity to the flange of the base member or stator and also that the cover is arranged very close to the outer edge of the ribs 30. These parts are carefully machined to accurate dimensions and on account of this accuracy, we are able to make a device which is more simple than others with which 95 we are familiar.

Having thus described our invention, we claim:

1. The combination with a siren including a pivoted body, an operating member for swinging said body, said member being connected at one end to said siren, a pivoted bell crank, said member being connected at the other end to said bell crank, means to rock said bell crank, said connection between said member and said bell crank including parts mounted for sliding movement and a spring for urging said member to one position.

2. In a siren, a body portion including a stator, a shaft mounted in said stator, a rotor mounted on said shaft, a disc on said rotor shaft for driving said rotor, said body having a lug thereon, said lug being arranged between said rotor and said disc and having an aperture therein arranged at one side of said shaft, a supporting shaft, said aperture being fitted on said shaft whereby said stator may turn, and means on said supporting shaft for holding it in 115 position.

3. In a siren, a body, a member on which said body is mounted for swinging movement, means to swing said body about said member to driving position, said means comprising a universal connection secured on said body, a link connected to said universal connection, a bell crank, a pin on said bell crank, said link passing through said pin, said link extending beyond said pin and hav- 125 130

- ing a spring thereon, said spring engaging said pin at one end, and means on said link at the other end of said spring to hold said spring.
4. In a siren, a body portion including a stator, a shaft mounted in said stator, a rotor mounted on said shaft, means to drive said rotor, said body having a lug thereon, said lug having an aperture therein arranged at one side of said shaft, a supporting shaft passing through said aperture, a foot on said supporting shaft for holding it in position and means to adjust said lug longitudinally of said supporting shaft, said means comprising an upper and a lower collar movable along said shaft and means to lock said collars in adjusted position.
5. In a siren, a body including a stator, a shaft mounted in said stator, a rotor mounted on said shaft, means to drive said rotor, said body having a lug thereon, said lug having an aperture therein, a supporting shaft passing through said aperture, means to support said supporting shaft, means to adjust said lug longitudinally of said supporting shaft, said means comprising an upper and a lower collar movable along said shaft, means to lock said collars in adjusted position, means comprising an upper and a lower collar movable along said shaft, and means to limit the movement of said body with respect to said supporting shaft.
6. In a siren, a body portion including a stator, a shaft mounted in said stator, a rotor mounted on said shaft, means to drive said rotor, said body having a lug thereon, said lug having an aperture therein, a supporting shaft passing through said aperture, a foot on said supporting shaft for holding it in position, means to adjust said lug longitudinally on said supporting shaft, said means comprising an upper and a lower collar movable along said shaft, means to lock said collars in adjusted position, means to limit the movement of said body with respect to said supporting shaft, said shaft having a spring thereon, said spring at one end being fixed with relation to said supporting shaft and at the other end being fixed with relation to said body whereby said spring exerts a turning action to turn said body about said supporting shaft.
7. In a siren, a body including a stator, a shaft mounted to rotate in said stator, a rotor fixed on said shaft, said body having an apertured lug thereon, said aperture being arranged at one side of said shaft, a supporting shaft passing through said aperture, means engaging said supporting shaft for supporting the body, said means including a portion for coacting with said body for maintaining said body in proper position with respect to said supporting shaft.
8. In a siren, a body including a stator, a shaft mounted in said stator, a rotor mounted on said shaft, means to drive said rotor, said body having a lug thereon, said lug having an aperture therein, a supporting shaft passing through said aperture, means engaging said shaft and said body to hold the shaft and body in assembled relation for rotary movement, said means including a bearing surface and means to limit rotary movement of said body relative to said supporting shaft.
9. In a siren, a body portion including a stator, a shaft mounted in said stator, a rotor mounted on said shaft, means to drive said rotor, said body having a lug thereon, said lug having an aperture therein arranged at one side of said shaft, a supporting shaft passing through said aperture, means to hold said supporting shaft in operative position, said means comprising an upper and a lower member surrounding said shaft and engaging the top and bottom of the lug, said lower member having a bearing surface thereon on which said lug engages.
10. In a siren a body including a stator, a shaft mounted in said stator, a rotor mounted on said shaft, said body having an apertured lug thereon, said aperture being arranged at one side of said shaft, a supporting shaft passing through said aperture, means to support said supporting shaft, said means including a fixed member through which said shaft passes, said member having a portion thereon for coacting with said body for maintaining said body in proper position with respect to said supporting shaft, and resilient means engaging said body and said supporting means to swing said body in one direction to actuate said rotor.
11. In a siren, a support, said support having a shaft thereon, a body, a rotor mounted in said body, means to mount said body on said shaft for pivotal movement, a shaft for said rotor, said rotor shaft being arranged at one side of said first mentioned shaft, means to drive said rotor shaft, means to swing said body on said first mentioned shaft and means to limit the swinging movement of said body on said shaft, said means including a stop member on the body and an adjustable member coacting with the stop member and adjustably mounted on the shaft.
- In testimony whereof, we hereunto affix our signatures.

LESTER H. MILES.
JAMES W. BAYLESS.
